SLING AND END FITTING

Frederick W. von Wehrden, St. Louis, Mo., assignor to Broderick & Bascom Rope Company, St. Louis, Mo., a corporation of Missouri

Application November 1, 1945, Serial No. 626,049

18 Claims. (Cl. 287—81)

1

This invention relates to the end fitting constructions of slings, particularly braided or plaited wire rope slings with end loops that fit around end fittings. It has for its principal object to provide a shackle or clevis-type end fitting construction for the above type of sling that is strong and durable, light in weight, simple and economical and is readily assembled from two corresponding rope thimbles adapted to support the end loops of the sling throughout their entire length and to provide aligned shackle pin openings in the outer end portion of said fitting. The invention consists in the sling and end fitting construction and in the parts and combinations and arrangements of parts hereinafter described and claimed.

In the accompanying drawing, which forms part of this specification wherein like symbols refer to like parts wherever they occur,

Fig. 1 is a side face view of a plaited or braided wire rope sling provided with an end fitting construction embodying my invention.

Fig. 2 is a side edge view of the sling and end fitting construction.

Fig. 3 is a fragmentary central longitudinal section through the outer or shackle pin receiving portion of the fitting on line 3—3 in Fig. 1; and

Figs. 4 and 5 are cross sectional views on the lines 4—4 and 5—5, respectively, in Fig. 2.

In the accompanying drawing my invention is shown embodied in a sling comprising an eight plaited or braided wire rope 1 terminating at one end of the sling in four loops 2. The sling is provided with a shackle or clevis-type end fitting preferably comprising two corresponding rigidly connected rope thimbles 3 that are spaced apart at the outer end of said fitting and are brought together in side-by-side relation at the inner end thereof. Each of the thimbles 3 is preferably made of a bar of channel-shaped cross-section that is bent at its middle to form a semi-circular outer end portion 4 and converging side portions 5 that meet at the inner end of said thimble, the channel of the bent bar facing outwardly and forming an exterior rope groove 6 that extends from said inner end of said thimble along said side portions and around said semi-circular outer end portion. The converging side portions 5 of each thimble are welded together as at 7, at the inner end thereof; and said converging side portions are also connected together adjacent to the semi-circular outer end portion 4 of said thimble by a cross piece 8 that fits between and is welded, as at 9, to the opposing faces of said side portions. The cross or bridge piece 55

2

8 is curved endwise so as to form with the curved outer end portion 4 of the thimble a substantially circular transverse shackle pin receiving opening 10. Each of the thimbles 3 also has its converging side portions 5 bent laterally, as at 11, at an oblique angle from a point inwardly of the cross piece or bridge 8 to a point adjacent to the inner end of said thimble where said side portions preferably terminate in end portions 12 that are disposed parallel with the forward portions of said side portions.

The two thimbles 3 are assembled to form the shackle or clevis-type end fitting by cross connecting said thimbles together with their outer 15 end portions in spaced parallel relation, with their laterally bent portions 11 converging toward the inner end of the fitting and with their parallel inner ends 12 in contact sidewise. The means for rigidly connecting the two thimbles

20 together preferably comprises a cross or bridge piece 14 that fits between the spaced parallel forward portions of said thimbles at the place where they converge toward each other and is welded, as at 15, to the opposing side faces thereof. Said securing means also includes a weld 16 that secures the parallel inner ends 12 of the two thimbles directly together in side-by-side relation.

As shown in the drawing, the four end loops 2 of the sling are separated or divided into two 30 pairs with the loops of each pair fitting one upon the other in the external groove 6 of each thimble and with the converging portions of each loop merging into the main body portion of the sling 35 at the inner end of the fitting. As shown in the drawing, the channel or grooves 6 of the end fitting are bridged or covered, as at 17, at the inner end of the fitting and also, as at 18, adjacent to the connecting bridge 14 for the two thimbles.

The hereinbefore described sling and end fitting construction has several important advantages. The loops of the sling are supported throughout their entire length in the two grooves 45 of the end fitting and cooperate therewith to divide the load equally between the two forks thereof and hold the converging portion of said loops in position to merge into the body of the sling. The loops are in tension and thus tend to hold the forks of the end fitting under compression against strains which tend to spread or distort them. The two thimbles are of the same size and shape and are quickly and easily secured together to form a shackle or clevis-type end fitting of strong, simple and economical con-

struction. The size of the fitting may be varied by using thimbles of different sizes. The cross members adjacent to the outer ends of the thimbles serve to strengthen them and they also cooperate with said ends to form aligned transverse holes in the forks of the fitting for a shackle pin 19. The hereinbefore described construction also eliminates the heavy and expensive forged or cast one-piece clevis-type end fittings heretofore employed; and it also eliminates the zinc filled socket constructions heretofore required for anchoring the sling to such fittings.

Obviously, numerous changes may be made without departing from the invention and I do not wish to be limited to the precise construction shown.

What I claim is:

1. In combination, a single rope and an end fitting therefor, said end fitting comprising a plurality of separately formed rope thimbles that are spaced apart at one end of said fitting and have aligned openings therethrough and are brought together and rigidly united in side-by-side non-communicating relation at the other end thereof, said rope terminating at one end in a plurality of closed loops, each positioned about one of said thimbles.

2. In combination, a single wire rope and an end fitting therefor, said end fitting comprising a pair of separately formed corresponding rope thimbles that are spaced apart at one end of said fitting and have aligned openings therethrough and are brought together and rigidly united in side-by-side non-communicating relation at the other end thereof, said rope terminating at one end in a pair of closed loops, each positioned about one of said thimbles.

3. In combination, a single braided wire rope sling and a shackle-type end fitting therefor, said end fitting comprising two separately formed thimbles that are spaced apart at one end of said fitting and have aligned shackle pin openings therethrough and are brought together and rigidly united in side-by-side non-communicating relation at the other end thereof, said braided wire rope terminating at one end in two closed loops, one positioned about each of said thimbles.

4. In combination, a single braided wire rope sling and a shackle-type end fitting therefor, said end fitting comprising two separately formed thimbles that are spaced apart at one end of said fitting and have aligned shackle pin openings therethrough and are brought together and rigidly united in side-by-side non-communicating relation at the other end thereof, said braided wire rope terminating at one end in two loops, one positioned about each of said thimbles, and a cross member rigidly uniting said thimbles between the spaced portions thereof.

5. In combination, a braided wire rope sling and a shackle-type end fitting therefor, said end fitting comprising two exteriorly grooved thimbles that are spaced apart at one end of said fitting and are brought together in side-by-side relation at the other end thereof, the spaced portions of said thimbles being shaped to provide substantially circular shackle pin receiving holes therein, and connecting means for said thimbles comprising a bridge piece connecting the spaced portions thereof and means connecting the portions thereof that are brought together in side-by-side relation, said braided wire rope terminating at one end in two loops, one positioned in the external groove of each of said thimbles.

6. In combination, a braided wire rope sling and a shackle-type end fitting therefor, said end fitting comprising two exteriorly grooved thimbles that are spaced apart at one end of said fitting and are brought together in side-by-side relation at the other end thereof, the spaced portions of said thimbles being shaped to provide substantially circular shackle pin receiving holes therein, and connecting means for said thimbles comprising a bridge piece connecting the spaced portions thereof and welds connecting the portions thereof that are brought together in side-by-side relation, said braided wire rope terminating at one end in two pairs of loops, the loops of one pair being positioned one over the other in the external groove of one of said thimbles and the loops of the other pair being similarly positioned in the external groove in the other of said thimbles.

20 7. The combination, a rope and an end fitting therefor, said end fitting comprising a plurality of separately formed rigidly connected rope thimbles that are spaced apart at one end of said fitting and converge from their spaced apart portions toward the other end of said fitting where they contact sidewise in non-communicating relation, said rope terminating at one end in a plurality of closed loops, each fitting around one of said thimbles.

30 8. In combination, a rope and a shackle-type end fitting therefor, said end fitting comprising two rigidly connected exteriorly grooved thimbles, each having a substantially semi-circular end portion and portions substantially tangent thereto that converge toward and are substantially in contact at the other end of said thimble, said semi-circular end portions of said thimbles being spaced apart at one end of said fitting and said converging portions converging toward the other end of said fitting where they contact sidewise, said rope terminating at one end in two loops, one positioned in the external groove of one of said thimbles and the other positioned in the external groove of the other of said thimbles.

40 9. In combination, a rope and a shackle-type end fitting therefor, said end fitting comprising two rigidly connected exteriorly grooved thimbles, each having a substantially semi-circular end portion, portions substantially tangent thereto that converge toward and are substantially in contact at the other end of said thimble, and a portion connecting said converging portions adjacent to said semi-circular end portion and cooperating therewith to form a shackle pin receiving opening, said semi-circular end portions of said thimbles being spaced apart at one end of said fitting and said converging portions converging toward the other end of said fitting where they contact sidewise, said rope terminating at one end in two loops, one positioned in the external groove of one of said thimbles and the other positioned in the external groove of the other of said thimbles.

50 10. An end fitting for a rope comprising a plurality of separately formed rigidly connected rope thimbles that are spaced apart at one end of said fitting and have aligned openings therethrough and are brought together and rigidly united in side-by-side non-communicating relation at the other end thereof.

60 11. A shackle-type end fitting for a rope sling comprising two separately formed thimbles spaced apart at one end of said fitting and brought together in side-by-side non-communicating relation at the other end thereof, and securing means

for said thimbles including a cross member between the spaced portions thereof.

12. A shackle-type end fitting for a braided wire rope sling comprising two exteriorly grooved thimbles spaced apart at one end of said fitting and brought together in side-by-side relation at the other end thereof, the spaced portions of said thimbles being shaped to provide substantially circular shackle pin receiving holes therein, and connecting means for said thimbles comprising a bridge piece connecting the spaced portions thereof and welds connecting the portions thereof that are brought together in side-by-side relation.

13. An end fitting for a rope comprising a plurality of separately formed rigidly connected counterpart rope thimbles that are spaced apart at one end of said fitting and converge from their spaced apart portions toward the other end of said fitting where they contact sidewise in non-communicating relation.

14. A shackle-type fitting for a braided wire rope sling comprising two rigidly connected exteriorly grooved thimbles, each having a substantially semi-circular end portion and portions substantially tangent thereto that converge toward and are substantially in contact at the other end of said thimble, said semi-circular end portion of said thimbles being spaced apart at one end of said fitting and said converging portions converging toward the other end of said fitting where they contact sidewise.

15. A shackle-type fitting for a braided wire rope sling comprising two rigidly connected exteriorly grooved thimbles, each having a substantially semi-circular end portion, portions substantially tangent thereto that converge toward and are substantially in contact at the other end of said thimble, and a portion connecting said converging portions adjacent to said semi-circular end portion and cooperating therewith to form a shackle pin receiving opening, said semi-circular end portion of said thimbles being spaced

apart at one end of said fitting and said converging portions converging toward the other end of said fitting where they contact sidewise.

16. An end fitting for a rope comprising a body having laterally spaced arms at one end thereof and having two laterally spaced non-communicating rope grooves that extend along two opposite sides of said body along the respective arms thereof and around the outer ends of said arms and converge toward the other end of said body.

17. An end fitting for a rope comprising a body with laterally spaced arms at one end thereof and two laterally spaced non-communicating rope grooves that extend along two opposite sides of said body along the respective arms thereof and around the outer ends of said arms and have portions that converge towards the other end of said body, the two portions of each individual groove also converging towards said other end of said body.

18. In combination, a braided wire rope sling and a shackle type end fitting therefor, said end fitting comprising two separately formed thimbles having openings extending therethrough, said braided wire rope terminating at one end in two closed loops, one positioned about each of said thimbles, and a shackle pin extending through said openings in said thimbles.
